UNITED STATES PATENT OFFICE.

ELIJAH B. MARTINDALE, OF INDIANAPOLIS, INDIANA.

SHEAVE-WHEEL.

SPECIFICATION forming part of Letters Patent No. 286,322, dated October 9, 1883.

Application filed May 7, 1883. (No model.)

To all whom it may concern:

Be it known that I, ELIJAH B. MARTINDALE, a citizen of the United States, residing at Indianapolis, in the county of Marion, in the 5 State of Indiana, have invented certain new and useful improvements in the construction and mode of manufacture of sheave-wheels or pulleys for cables to run upon, of which the following is a specification.

10 My said invention consists of a combination sheave-wheel made of iron and paper, pasteboard, or other like material. The wheel, including the hub, arms, rim, and a flange on one side of the rim, is of iron, cast in one piece. 15 The paper, pasteboard, or other like material is cut into rings of sizes to exactly fit over the rim. These rings are pasted together and subjected to heavy pressure until they are compact and solid, forming a complete covering 20 for the iron rim. A movable flange, of iron, is cast corresponding to the flange already cast on one side of the rim. This is so made that it can be securely fastened to its place on one side of the rim with rivets or bolts. The solid 25 paper ring is then forced upon the cast-iron rim, and then the movable iron flange is secured to its place. The paper ring is thus held firmly upon the rim, and forms the bearing- 30 surface or bed upon which the cable runs. Paper, pasteboard, or other like material is thus substituted as a facing for the cable to run upon for rubber or Babbitt metal, as has been heretofore used.

Referring to the accompanying drawings, 35 which are made a part hereof, and on which

similar letter of reference refer to similar parts, Figure 1 is a side elevation of sheave-wheel made in the manner indicated. Fig. 2 is a section thereof, and Fig. 3 shows the wheel with one detached flange.

The portion marked A is the hub, which may be cast to fit upon a shaft, or with projecting pintles as a substitute for a shaft. B B are arms. C is the rim; D, the flange cast with the rim; E, the ring or facing, of paper, pasteboard, or other like material; F, the movable flange; G, the bolts or rivets securing the movable flange to the rim. The edge of the paper being the part upon which the cable rests, it will wear much longer than Babbitt metal or rubber, and is much cheaper than either; and when the paper facing wears out the flange may be removed and a new ring substituted.

Having thus fully described my said invention, what I claim, and desire to secure by Letters Patent, is—

1. A combination sheave-wheel for cables to run upon, made of iron and paper, pasteboard, or other like material, and having a facing of the edge of the paper, pasteboard, or other like material, substantially as set forth.
2. A paper facing for a sheave-wheel on which the cable runs, secured to the periphery of a cast-iron wheel by means of a movable flange, substantially as set forth.

ELIJAH B. MARTINDALE.

In presence of—

LYNN B. MARTINDALE,
LOUIS A. BUDENZ.
